US00D651049S

(12) **United States Design Patent**
Nakagawa

(10) **Patent No.:** US D651,049 S
(45) **Date of Patent:** ** Dec. 27, 2011

(54) **BEVERAGE COOLER**

(75) Inventor: **Shuji Nakagawa**, Otsu (JP)
(73) Assignee: **Masatoshi Imai**, Kyoto-shi (JP)
(**) Term: **14 Years**
(21) Appl. No.: **29/356,227**
(22) Filed: **Feb. 22, 2010**

(30) **Foreign Application Priority Data**

Nov. 27, 2009 (JP) 2009-027694
(51) **LOC (9) Cl.** 07-01
(52) **U.S. Cl.** D7/603
